UNITED STATES PATENT OFFICE.

EDWARD G. KELLEY AND CHARLES ZIRKLE, OF GREENVILLE, OHIO.

AUTOMATIC VALVE.

Application filed June 30, 1925. Serial No. 40,583.

To all whom it may concern:

Be it known that we, EDWARD G. KELLEY and CHARLES ZIRKLE, citizens of the United States, residing at Greenville, in the county 5 of Darke and State of Ohio, have invented certain new and useful Improvements in Automatic Valves, of which the following is a specification.

This invention relates to valves and pertains particularly to an automatic air valve for use in connection with seat action toilets making use of a compression tank.

The primary object of this invention is the provision, in a manner as hereinafter set forth, of an automatic air valve for use with a toilet compression tank, by means of which air will be admitted to the tank when the water is flowing therefrom and will be trapped therein upon the refilling of the tank, becoming compressed by the inflowing water and thus held in the compressed condition until the tank is again empty. The air thus compressed in the tank will assist in the ready and complete evacuation of the same upon the flushing of the toilet.

A further object of the invention is the provision, in a manner as hereinafter set forth, of an automatic air valve for the use above set forth, in which, in the event that through some defect the valve ceases to operate, the valve will become closed so that no air can enter the compression tank thus causing the imperfect action of the tank and drawing attention to the fact that the valve is not operating properly.

A further and final object of the invention is the provision, in a manner as herein-after set forth, of an automatic air valve for the purpose above set forth, which will be of simple construction, strong and durable, and efficient for the purpose for which constructed.

The invention will be best understood from a consideration of the following detailed description taken in connection with the accompanying drawing forming a part of this specification, with the understanding that the invention is not confined to any strict conformity with the showing of the drawing but may be changed and modified so long as such changes and modifications mark no material departure from the salient features of the invention as expressed in the appended claims.

In the drawing:

Figure 1 shows the device embodying this invention, in side elevation.

Figure 2 is a longitudinal sectional view through the device. 60

Figure 3 is a top plan view of the same.

Figure 4 is a plan view of the float and check element forming a part of the interior construction of the valve.

Figure 5 is a section taken upon the line 65 5-5 of Figure 2.

Figure 6 is a side elevation of the check valve used in the main valve structure and,

Figure 7 is the bottom plan view of the check shown in Figure 6. 70

Referring now to the drawing in detail wherein like numerals of reference indicate corresponding parts throughout the several views, the device embodying this invention comprises a head 1, the lower portion of which head is constricted as indicated at 2 and terminates in the reduced annular portion 3. The upper or larger portion of the head 1 is hollowed to provide the longitudinally extending chamber 4, the upper portion of which chamber has the wall thereof threaded as indicated at 5. The lower portion of the head has a central longitudinally extending recess 6 formed therein, the inner wall of which is threaded as indicated at 7, and connecting this recess 6 with the lower portion of the chamber 4 is a passage 8 of less diameter than the diameter of the recess 6, and the lower portion of this passage is threaded as indicated at 9. 75 80 85

Threaded at one end in the recess 6, is a nipple 10 each end of which is peripherally threaded as indicated at 11, and engaged over the other end of this nipple 10 is a reducing coupling 12 into the reduced end 13 95 of which a second nipple 14 of less diameter than the nipple 10, is threaded. This nipple 14 also has each end threaded as indicated at 15, and the other free end of this nipple is adapted to be connected to and lead 100 into a compression tank (not shown).

Threaded into the passage 8 and engaging threads 9 formed in the wall thereof is a relatively long tube 16, the lower end of which is reduced as at 17 and headed as 105 shown, to receive thereover the open end of a rubber check 18. This check has an annular groove 19 formed thereabout in which a securing wire 20 is adapted to be placed, which ends of the wire are twisted to hold 110

the open end of the check securely in engagement with the headed reduced end of the tube 16. The check 18 has formed upon and across the other end the thickened ridge 21 and there is formed in this ridge the slit 22 which opens into the interior of the check as clearly shown in Figure 2. As will be explained further on this check allows air to pass from the tube 16 into the nipples 10 and 14 and the coupling 12 and prevent any air from flowing back from these elements into the tube.

10 The upper open end of the chamber 4 is closed by a plug indicated generally by the numeral 23. This plug comprises an enlarged peripherally threaded annular portion 24 and a polygonal shaped extension 25. Extending longitudinally through the extension 25 of the plug is a bore 26 the lower 20 end of which opens into the annular recess 27 which is of greater diameter than the bore as is shown in Figure 2 and this annular recess in turn opens into the arcuately recessed lower side of the enlarged portion 24 of the plug as indicated at 28.

15 Extending longitudinally through the plug 23 and through the chamber 4 of the head 1, is a rod member 29 threaded throughout as shown. At approximately 30 the central portion of this rod there is positioned a float 30, through the central portion of which the rod passes and upon the lower side of this float is a retaining plate 31 held in position and in turn holding the 35 float in position upon the rod by means of the nut 32.

20 Upon the top of the float 30 is a semi-spherical rubber seat washer 33, the flat surface of which bears against the top of the 40 float 30 while the curved portion is adapted to seat against the edge formed in the plug between the recesses 27 and 28, under certain conditions. The threaded rod 29 passes through this washer as is shown.

25 Threaded upon the rod 29 is a securing nut 34 which bears against the top of the washer 33 and over this nut is a cup washer 35 held in position by the nut 36. This cup washer under certain conditions, when the washer 33 seats upon its seat, moves into and 50 closes the annular recess 27.

30 Upon the upper end of the threaded rod 29 which extends beyond the top of the plug portion 25 is a pair of stop nuts 37 which 55 prevent the rod 29 and elements carried thereon from moving downwardly further than is desired.

35 The top surface of the polygonal extension 25 of the plug is transversely slotted as indicated at 38 thus when the nuts 37 are resting upon the top of the portion 25 they will not close the aperture or passage 26 against the passage of air therethrough as the air will enter the passage 26 through 65 the slit 38.

This valve structure just described is adapted to be attached to a compression tank of a seat action toilet, and when the toilet is flushed the vacuum created in the tank through the water leaving the discharge port thereof will cause air to be drawn in through the passage 26 past the open valves 33 and 34 and through the chamber 4 and tube 16, through the check 18 and into the tank. When the tank has become completely empty of water, it will then be filled with air and due to the closing of the slit 22 in the check 18 this air in the tank will be trapped and cannot leave the same. When the water begins to flow into the tank to refill the same it will compress the air trapped therein as it rises and thus when the tank is again flushed this compressed air will act to forcefully eject the water from the tank into the toilet bowl thus causing a complete and better flushing of the bowl than would be obtained if the water flowed from the tank through gravity only.

30 Under all normal conditions the float 30 will be down and the valves 33 and 34 will be unseated. In the event that the check 18 fails, through the rotting of the rubber or from any other cause which would allow the water from the tank to flow back up through the tube 16 into the chamber 4 instead of being stopped by the check the float would be raised by the water raising the valves 33 and 34 to close the passage through the cap 23 thus preventing the water from escaping through the valve. The cup valve 34 will be forced into the recess 27 when this happens and will frictionally engage the wall thereof, and when the tank is flushed and water leaves the same the frictional contact of this cup valve 34 will prevent the float and valve from dropping thus preventing the air from being drawn into the tank as the water leaves the same. This will cause a faulty operation of the tank and will indicate that the valve is not working properly so that an immediate repair can be made to the valve to restore the normal working condition of the same.

35 Having thus described our invention what we claim is:—

1. A valve of the character described comprising, a chambered head, tubular means carried thereby and opening into the chamber for connecting the head to a compression flush tank, said head having an air inlet thereinto, check means arranged in said tubular means allowing air to pass into said tank through said head, and means for closing said air inlet to said head in the event of the failure of said check.

2. A valve of the character described comprising, a head having a chamber formed longitudinally therein, a centrally apertured plug closing the open end of said chamber, means for setting up a tubular connection

between said chamber and a toilet compression flush tank, means in said tubular connection allowing air to flow only through said head into said tank, and automatically 5 operating means for closing the aperture in said plug in the event of the failure of said means in the tubular connection.

3. A valve of the character described comprising, a head having a chamber formed longitudinally therein, a centrally apertured plug closing the open end of said chamber, means for setting up a tubular connection between said chamber and a toilet compression flush tank, means in said tubular connection allowing air to flow only through said head into said tank, and a float element 10 within said chamber acting to bring about the closure of the aperture in said plug in the event of the failure of said check.

15 4. A valve of the character described, comprising, a head having a chamber formed longitudinally therein, a centrally apertured plug closing the open end of said chamber, means for setting up a tubular connection between said chamber and a toilet compression flush tank, a one way check in said tubular connection allowing air to flow only 20 through said head into said tank, a shiftable rod extending longitudinally through said chamber and through the aperture of said plug, a float carried upon said rod adapted to be shifted by water backing into 25 said chamber from said tank, in the event of the failure of said check, means carried by said rod operating to close the said aperture when said float is raised, and means engaging the wall of said aperture, upon the closing of the same by said last mentioned means, whereby the aperture will be maintained closed independent of the operation 30 of said float.

be shifted by water backing into said chamber from said tank, in the event of the failure of said check, and means carried by said rod operating to close the said aperture 35 when said float is raised.

5. A valve of the character described, comprising, a head having a chamber formed longitudinally therein, a centrally apertured plug closing the open end of said chamber, 40 means for setting up a tubular connection between said chamber and a toilet compression flush tank, a one way check in said tubular connection allowing air to flow only 45 through said head into said tank, a shiftable rod extending longitudinally through said chamber and through the aperture of said plug, a float carried upon said rod adapted to be shifted by water backing into 50 said chamber from said tank, in the event of the failure of said check, means carried by said rod operating to close the said aperture when said float is raised, and means engaging the wall of said aperture, upon the closing of the same by said last mentioned 55 means, whereby the aperture will be maintained closed independent of the operation of said float.

In testimony whereof, we affix our signatures hereto.

EDWARD G. KELLEY.
CHARLES ZIRKLE.
